UNITED STATES PATENT OFFICE.

ALONZO G. SHARP, OF COLUMBUS, OHIO, ASSIGNOR TO THE E. M. HULSE COMPANY,
OF COLUMBUS, OHIO, A CORPORATION OF OHIO.

SOFA OR DAVENPORT BED.

1,121,298.

Specification of Letters Patent. Patented Dec. 15, 1914.

Application filed June 10, 1911. Serial No. 632,343.

To all whom it may concern:

Be it known that I, ALONZO G. SHARP, a citizen of the United States, residing at Columbus, in the county of Franklin and State of Ohio, have invented a certain new and useful Improvement in Sofa or Davenport Beds, of which the following is a specification.

The object of this invention is to provide an improved construction of sofa or davenport bed in which the parts are of simple and economical construction and easy operation.

The invention is embodied in the construction and combination of parts set forth in the following description and pointed out in the appended claims.

In the accompanying drawing forming part hereof—Figure 1 is a side view of the mechanism at one end of the bed showing the open or extended position of the bed. Fig. 2 is a similar view of the mechanism in closed position. Fig. 3 is a front view showing one of the front legs. Fig. 4 is a detail in top plan view of one of the middle supports at the end. Fig. 5 is a front view of the same. Fig. 6 is a detail to show the form of the slot in the end of the outer section of the folding bed.

Fig. 10 designates one of the forward corners of a rectangular box or frame that is bolted at 10^a to usual ornamental end pieces 11.

The character 12 designates the corresponding corner of the seat frame which is also of rectangular form and suitably upholstered. The seat frame 12 is hinged to the forward edge of the box as indicated at 12^a. The spring bed frame is foldable and comprises an inner section 13, an outer section 14 and middle or connecting-sections 15 hinged to the sections 13 and 14. The spring bed frame is mounted or supported on the box frame 10 and on the under side 45 of the seat frame 12 so that by manipulating the seat frame only the spring bed can be opened and closed. The mechanism for effecting the opening and closing of the spring bed frame is the same at each end of the structure so that a description and illustration of one will suffice for both. I will now describe said mechanism as it appears at one end of the structure.

Connecting the inner bed section 13 with the box frame 10 is a long bar 16 and a short

bar 17. These two bars are hinged together at 17^a and to the bed section 13 and box frame 10 respectively. These bars serve to support the said bed section at the proper level at the rear end when the bed is opened. Springs 18 connect the rear of the said bed section with the back or end connecting pieces of the structure and serve to hold the said bed section up off the floor when the bed is turned in or closed. These springs 18 because stretched when the bed is closed also assist in raising the inner section of the bed when it is opened.

Journaled in ears 19 and 19^a, at each forward corner of the box frame 10 is a rocking frame or standard 20 that is hingedly connected at its upper end to the middle or connecting section 15 of the bed. This rocking standard 20 has rigidly secured to it an arm 21, and connecting the arm 21 with the seat frame 12 is a link 22 hingedly connected to both. The end of the outer bed-frame section 14 is provided with a slot 23 having on its upper wall a notch 23^a, and connecting the said bed section and the seat frame is an arm 24 hinged to the seat frame and having a pin 24^a that extends through said slot 23 thus providing a sliding connection between the arm and bed section. Connected with the inner end of the pin 24^a and the bed section is a coiled spring 25 that tends to draw the pin 24^a into the notch 23^a when the bed is opened. The slot 23 permits the bed section to move with reference to the pin 24^a when the bed is opened and closed, but when the bed is fully opened the engagement of the pin 24^a with the notch 23^a provides a support for the end of the bed section holding the latter at the proper level.

When the bed is opened the edge of the seat is supported by means of legs like that shown at 26. This leg is pivoted to a plate at 26^a and is automatically operated by a link 27 that is eccentrically connected with the leg and slidably connected with the front bar of bed frame section 14. When the bed is opened the separation of the spring bed section 14 and the seat frame 12 causes the leg 26 to assume an erect position, and conversely when the bed is closed and the bed section 14 and seat frame 12 approach each other the leg is thrown up alongside the bar of the bed section 14 as indicated in Figs. 1, 2 and 3.

The operation is very simple. To open

the bed the seat is taken by the usual strap at its free edge as appears in Fig. 2 and turned out to the position shown in Fig. 1. To close the bed the seat is turned inward 5 from the position shown in Fig. 1 until it assumes the position shown in Fig. 2. In these two manipulations the operating parts assume substantially the positions illustrated as the open and closed positions respectively in Figs. 1 and 2. The rocking standards 20 permit the extension of the spring bed frame with great ease and permit an ample outward projection of the bed when opened. The room provided for the 15 mattress and bed clothing between the bed frame sections is ample and such clothing does not interfere with the operation of the mechanism.

In this construction it will be observed 20 that all the operating mechanism is mounted upon the box frame 10 and seat 12, hence the bed can be shipped unmounted and is easily assembled by the retail dealer. Of course, the back may be provided with a suitable 25 top rail and with a suitable upholstered frame as well understood by those skilled in the art.

What I claim is:

1. In a sofa or davenport bed, the combination

with a box frame and a seat frame 30 hinged to the forward portion thereof, of a folding spring bed frame including a middle section, rocking standards journaled in the box frame and connected with said middle section, means connecting said rocking 35 standards with the seat for operation thereby, and bars connecting the inner and outer sections of the spring bed frame with the box frame and seat respectively, the connection of the bars with the outer section being 40 a spring held sliding one, substantially as described.

2. In a sofa or davenport bed, the combination with the stationary frame and a seat frame hinged thereto, of a folding mattress frame, and a rocking standard therefor journaled at one end directly on the stationary frame and hingedly connected at its other end with the folding mattress frame, said standard having an arm rigid therewith extending therefrom and a simple link connection 22 connecting said rigid arm with the seat frame.

ALONZO G. SHARP.
